Primary Examiner — Catherine Tuttle(74) *Attorney, Agent, or Firm* — Abelman, Frayne & Schwab(57) **CLAIM**

The ornamental design for a toy, as shown and described.

DESCRIPTION

FIG. 1 is a front, top and side perspective view showing my new design for a toy;

FIG. 2 is a top plan view thereof;

FIG. 3 is an elevation view thereof, the opposing elevation view being the same; and,

FIG. 4 is an elevation view rotated 90° from FIG. 3, the opposing elevation view being the same.

The broken lines are included for the purpose of illustrating a portion of the toy that forms no part of the claimed design.
